UNITED STATES PATENT OFFICE.

JOHN INGERSON BROWN, OF WESTFIELD, MASSACHUSETTS.

SLOW-FEED MANGER.

1,229,026.

Specification of Letters Patent.

Patented June 5, 1917.

Application filed December 9, 1916. Serial No. 135,992.

To all whom it may concern:

Be it known that I, JOHN I. BROWN, a citizen of Canada, and a resident of Westfield, in the county of Hampden and State of Massachusetts, have invented a new and Improved Slow-Feed Manger, of which the following is a full, clear, and exact description.

This invention relates to mangers and particularly to what may be termed a semi-automatic feed manger, and has for an object the provision of means which will insure the discharge of feed from a storage reservoir into the manger proper.

Another object in view is to provide a manger which may be quickly applied and removed.

A still further object in view is to provide a manger having a main bowl and a storage compartment, together with means operable by the animal for insuring a proper feed from the storage compartment to the bowl.

In the accompanying drawing:—

Figure 1 is a longitudinal vertical section through a manger disclosing an embodiment of the invention.

Fig. 2 is a top plan view of a manger disclosing an embodiment of the invention, part thereof being broken away.

Fig. 3 is a section through Fig. 1 on line 3—3.

Fig. 4 is a detail fragmentary sectional view through Fig. 1 on line 4—4.

Referring to the accompanying drawing by numerals, 1 indicates a bracket which may be secured to the wall by screws or in any other desired manner, said bracket being arranged to accommodate the depending fingers 2 and 3 as shown in Figs. 2 and 3, said fingers being rigidly secured in any suitable manner to the band 4. Band 4 is intended to encircle the main bowl 5 and the storage compartment 6. The bowl 5 may be made in any suitable way, preferably by being formed from sheet metal and having a bead 7 at the upper end which rests against the band 4 whereby the bowl is supported and stiffened.

When the device is in use the grain is placed in the compartment 6 and is slowly fed into the bowl 5. In order that this feeding may be carried out the bowl 5 is provided with an opening 8 which may be closed entirely or partially by a sliding member or door 9 held in place by a clamp-

ing screw 10 and also, if desired, by the guiding members 11 and 12 which merge into a reinforcing member 13 carrying the projections 14 and 15. The projection 14 carries a pivotal pin 16, which pin extends through the finger 17 whereby said finger is pivotally mounted. Finger 17 is provided with a feeding nose 18 preferably wider than the remaining part of the finger so as to stir the grain immediately previous to its passage through opening 8 and thereby allow the free flowing of the grain under the action of gravity.

The upper end of the finger 17 is pivotally connected to the bar 19 by pin 20, said pin having a sufficient loose movement to allow a proper back and forth movement of bar 19, said movement being caused in one direction by spring 21 acting against the end of the hollow projection 15 and at the other end against the shoulder 22 formed on bar 19. Bar 19 at its inner or free end is provided with an enlargement or knob 23 adjacent which a washer 24 of yielding material is provided, preferably a rubber washer. This arrangement is such that when the horse or other animal is using the bowl 5 the animal may strike against the knob 23 and operate finger 17 for loosening the grain which sometimes becomes clogged adjacent the opening 8. This will allow the grain to flow freely into bowl 5 until the compartment 6 is empty. When any animal first uses the device the striking of knob 23 more or less often will be somewhat accidental, but usually horses and other animals will become sufficiently acquainted with the device to operate the same designedly.

In forming the container 6 the same is provided with a rear wall which merges into a bottom, said bottom being connected to the bowl 5 by any desired means, as for instance, by solder, while the front wall 26 preferably extends interiorly of the bowl 5, as shown in Fig. 1, one of said walls being provided with an angle plate 27 for supporting the lid 28. The top or lid 28 is connected to the outer wall 29 by a suitable hinge 30 and normally rests against the member 27, as shown in Fig. 1. A suitable slot 31 is provided in wall 26 and also in the wall of the bowl 5 for accommodating the clamping screw 10, whereby the clamping screw 10 not only clamps the door 9 in proper position but assists in clamping the

wall 26 against the wall of bowl 5. If desired, wall 26 may be riveted or otherwise secured to bowl 5 in addition to being clamped by screw 10.

5 In operation the container 6 is filled with grain and immediately a certain quantity flows into the bowl 5, the flowing action continuing until there is enough grain in the bowl 5 to act as a closure for opening 8. As soon as the animal has eaten the grain in the bowl 5, or part of the grain, some additional grain will feed into the bowl 5 to take the place of that removed. Sometimes the moisture in the grain will 10 cause it to clog near opening 8 or sometimes the grain, by reason of its form or construction, will clog. When this has been done a slight blow against the knob 23 will cause the nose 18 to move back and forth, which will break or stir the clogged 15 part of the grain, whereupon the same will again start to flow into bowl 5. In this

way the animal is insured of receiving the full amount of grain in the container 6 and is not supplied with an over-quantity at 20 any one time, whereby none of the grain is wasted.

What I claim is:

A manger of the character described, comprising a bowl, a container for feeding material into the bowl, a stirring member pivotally mounted in the container and arranged with one end adjacent the discharge section of the container, a spring for normally holding the stirring member in a pre-determined position, and a bar connected with the stirring member extending into the bowl, said bar being operable against the action of said spring whereby the stirring member is moved in one direction by 30 the bar and in the opposite direction by 35 the bar and in the opposite direction by 40 the bar.

JOHN INGERSON BROWN.
